UNITED STATES PATENT OFFICE

2,477,464

SAIL FABRIC

Albert R. Pierce, Jr., South Dartmouth, Mass.

Application June 6, 1946, Serial No. 674,840

3 Claims. (Cl. 139—383)

1

This invention relates to a sail such as is used upon yachts or ships and more particularly to the fabrication of the material which is incorporated in such a sail.

It is usual in the construction of sail fabric to provide a line adjacent each of the selvage edges of a woven material to determine the overlap of one web of material with the next web in joining these together for the formation of a sail. As the distance between selvages is of a substantial extent in order to strengthen the sail it is also usual to so-call "bight seam" the web at a point intermediate the selvages. The goods are usually perfectly plain between the selvages so that the bight seaming is a procedure consuming a considerable amount of time inasmuch as measurements must be made continually in order to provide the bight seam in such a position that after it is formed its center will be uniformly spaced between the selvage edges.

One of the objects of this invention is to provide a means by which the bight seam may be placed in the cloth much more quickly.

Another object of this invention is to provide lines in the fabric which will guide the formation of a bight seam so that when made it will be in the correct position with relation to the selvage.

More specifically an object of this invention is to locate warp threads of contrasting color with relation to the fabric of the sail cloth so that these threads will stand out and may serve as a guide for the folding of the cloth to form the bight seam.

With these and other objects in view, the invention consists of certain novel features of construction as will be more fully described and particularly pointed out in the appended claims.

In the accompanying drawings:

Fig. 1 is a perspective view of a fragmental portion of a web of fabric which has had a bight seam sewed therein and which has also been secured to other webs of fabric, which are fragmentally shown, at the selvage edges thereof;

Fig. 2 is a top plan view of a fragmental portion of a web of fabric showing the guiding lines woven therein;

Fig. 3 is a perspective view illustrating the first fold in the formation of the bight seam;

Fig. 4 is a similar view illustrating the more complete formation of the folds for the bight seam;

Fig. 5 is an edge view of a different arrangement of bight seaming; and

Fig. 6 is a plan view similar to Fig. 2 but illus-

2

trating a strip of stock marked for bight seaming such as shown in Fig. 5.

In proceeding with this invention, I mark the web of fabric which is to be used for sail cloth by inserting warp threads at the desired positions with reference to the width of the fabric so as to provide the guide lines desired. These threads may be of a color which will contrast with the usual color of the threads such for instance as the provision of a red marking thread in a generally white fabric.

With reference to the drawings, in the form of the invention shown in Figs. 1 and 2, the woven fabric is designated 10 and I have provided adjacent the selvage 11 a marking thread 12 while adjacent the other selvage 13 I have provided a marking thread 14. These threads 12 and 14 will be spaced equally from the selvage edges 11 and 13. The additional marking threads 15 and 16 are also provided intermediate the marking lines 12 and 14. An imaginary center line of the fabric is designated 17 and it will be apparent that the threads 15 and 16 are not symmetrical with reference to the center line 17. The spacing, however, is such that if the fabric is folded along the line 16 and this fold line is caused to register with the line 15, as shown in Fig. 4, the center of the bight seam thus formed will be in the center of the fabric, as shown in Fig. 1. Stitching will then occur to hold the fabric in this position. After the web or piece is bight seamed, it is sewed to other similar formed webs which are designated such as 20 and 21 by overlapping the edges so that the selvage of one will be positioned at the guide line either 12 or 14 of the other.

In the form of the invention shown in Figs. 5 and 6, the woven fabric is designated 30 and I have provided adjacent the selvage 31 a marking thread 32, while adjacent the other selvage 33 I have provided a marking thread 34. These threads 32 and 34 will be equally spaced from the selvage edges 31 and 33. In this example I provide for the forming of two bight seams intermediate the selvages by placing additional pairs of marking threads 35 and 36 and 37 and 38 between the threads 32 and 34. The location of the additional marking threads is such that if the fabric is folded along the line 36 and this fold line is caused to register with the line 35 similar to the folding above described and the fabric is also folded along the line 38 and this fold line is caused to register with the line 37 in the same manner, then the center of the bight seams 39 and 40 thus formed will be spaced from

the center of the margins 41 and 42 formed between each selvage 31 and 33 and their margin marking lines 32 and 34 the same distance they are from each other so as to equally divide the bight seaming.

This same layout may also be applied where there are other numbers of bight seams intermediate the selvages and so I lay out the intermediate marking lines according to a common formula for all cases dependent only upon knowing the spacing of the selvage marking lines and number of bight seams to be desired and place the additional intermediate pairs of marking lines in such location.

Thus the spacing of the first reference line 15 in Fig. 2 is calculated from the edge 13 of the fabric 10 according to the formula

$$\frac{w-a(2n+1)}{n+1}$$

where w is the total width of the fabric, a is the width of the space between the selvage 13 and the margin line 14, and n is the number of bight seams. The second reference line as 16 is always $2a$ from the first line which in the case of the single bight seam completes the layout, although it will be also found that the line 12 will also be the following distance from the first reference line 15.

$$\frac{w-a(2n+1)}{n+1} + 2a$$

A similar procedure is adopted for the location of the additional marking lines in Fig. 6. Thus the first line 35 of the pair is calculated from the edge 33 of the fabric 30 according to the same formula

$$\frac{w-a(2n+1)}{n+1}$$

and the second reference line 36 is $2a$ from the first line 35. The second set or pair of lines in this case where two bight seams are to be provided are similarly located. Thus the line 37 is located from the first reference line 35 according to the formula

$$\frac{w-a(2n+1)}{n+1} + 2a$$

and the companion line 38 is spaced $2a$ from this line 37. It may further be noted that the margin line 32 is spaced from the line 37 also a distance

$$\frac{w-a(2n+1)}{n+1} + 2a$$

This procedure may be used for any number of bight seams to be provided.

I claim:

1. Piece goods for the formation of a yacht sail comprising a length of woven fabric having a marking line inwardly from each selvage a distance a defining the width of overlap in sewing two widths of fabric together and additional marking lines for bight seaming provided in accordance with the number of bight seams to be used, there being at least one pair of lines, which pair of lines are spaced a distance $(2a)$ apart

with the spacing between a first selvage edge and the nearest line of the pair a distance represented by the formula

$$\frac{w-a(2n+1)}{n+1}$$

where w is the width of the fabric, a is the selvage mark width from the edge, and n is the number of bight seams in the width of cloth.

10 2. Piece goods for a yacht sail as set forth in claim 1 wherein said additional lines comprise contrasting warp threads woven into said fabric.

3. Piece goods for a yacht sail as set forth in claim 1 wherein each of said lines is formed by a contrasting warp thread woven into said fabric.

15 4. Piece goods for a yacht sail as set forth in claim 1 wherein each of said lines is formed by a contrasting colored warp thread woven into said fabric.

5. Piece goods for the formation of a yacht sail comprising a length of woven fabric having a marking line inwardly from each selvage a distance a defining the width of overlap in sewing

20 two widths of fabric together and additional marking lines for bight seaming, said lines being present in pairs in accordance with the number of bight seams to be provided and spaced a distance $(2a)$ apart which is twice that of said marking lines inwardly from each selvage edge of the fabric and the first line of the first of said

25 pair of lines being spaced from one selvage edge a distance represented by the formula

$$\frac{w-a(2n+1)}{n+1}$$

30 35 and the line of the next and each succeeding pair of lines which corresponds to the first of said pair of lines being spaced in increments from said first of said pair of lines a distance represented by the formula

$$\frac{w-a(2n+1)}{n+1} + 2a$$

40 where w is the width of the fabric, a is the selvage mark width from the edge, and n is the number of bight seams in the width of cloth.

45 6. Piece goods for a yacht sail as set forth in claim 5 wherein said additional lines comprise contrasting warp threads woven into said fabric.

7. Piece goods for a yacht sail as set forth in claim 5 wherein each of said lines is formed by a contrasting warp thread woven into said fabric.

50 8. Piece goods for a yacht sail as set forth in claim 5 wherein each of said lines is formed by a contrasting colored warp thread woven into said fabric.
